INVENTOR,
Frederick D. Kreuder

BY
Henry J. Lueke,
HIS ATTORNEY.

UNITED STATES PATENT OFFICE

FREDERICK D. KREUDER, OF BROOKLYN, NEW YORK

REINFORCEMENT FOR CONCRETE

Application filed April 12, 1929. Serial No. 354,475

This invention relates to re-enforcements for concrete.

A special feature of my present invention is the formation of wire re-enforcements for 5 soffits, the re-enforcements being formed of a plurality of sections of wire or other suitable material, to be assembled and connected for particular sizes of the assembled re-enforcements within predetermined ranges, for 10 use.

Pursuant to my invention, the individual re-enforcement sections are manufactured in quantity and assembled, usually in pairs, by welding such pairs to one another, and/or 15 to an interconnecting wire, in which latter case each multiple re-enforcement is carried by and spaced by its interconnecting wire.

Preferably, the individual re-enforcement sections are duplicates of one another.

Further features and objects of the invention will be more fully understood from the following detail description and the accompanying drawings, in which

25 Fig. 1 is a vertical sectional view through an I-beam illustrative of a structural element, showing a preferred form of an individual multi-section re-enforcement embodying my invention;

30 Fig. 2 is a perspective view, on an enlarged scale, of an individual re-enforcement section;

Fig. 3 is a top plan view of an interconnecting wire to which a plurality of pairs of re-enforcement sections are secured;

Fig. 4 is an elevation of a modified form of connected pair of re-enforcement sections;

Fig. 5 is a detail vertical sectional view, similar to Fig. 1, showing a further modification;

Figs. 6, 7 and 8 are elevational views of further modifications.

45 conventional form of I-beam, about its lower flange 10a a soffit of concrete is to be formed.

According to my invention, the reinforcement is formed of a plurality of sections, usually in pairs. In Fig. 1, the re-enforcement section 11 is paired with the re-enforcement section 12, the sections in this instance

being duplicates of each other. An individual reinforcement section of the form shown in Fig. 1 is illustrated in perspective on an enlarged scale in Fig. 2, and in detail comprises the body portion 13, the spacer portion 14, and the end portion 15. The end portion 15 in this instance is preformed as a clip to abut an edge face of the I-beam or other structural element, its terminal portion 16 being bent downwardly at an angle to locate its terminus 16a in contact with the upper face of the lower flange 10a of the I-beam 10 as appears in Fig. 1. Its inner end 17 is bent in any desired angle, usually at a right angle to the body portion 13 to locate its terminus 17a in contact with the lower flange face 11 of the I-beam or other structural element.

In the commercialization of the invention, such re-enforcement sections are manufactured in quantity and stocked and upon receipt of orders for definite sizes of I-beams or other structural elements, pairs or other multiples of such sections are assembled to the ordered sizes. The individual sections may be of varied dimensions for assembly for different ranges of dimensions of the structural elements. 70 75

The assembly and connection between the re-enforcement sections may be had by welding as indicated at 18, Fig. 1, or by other suitable procedure or connecting means. 80

It is advantageous to connect the pairs or other multiple re-enforcement sections to an interconnecting wire 19, see Fig. 3. : Usually, the respective pairs of sections are welded to the interconnecting wire at uniform spacings. Such interconnected form of my invention is advantageous in crating for shipment to the location of installation, and facilitates the handling to the individual multi-paired re-enforcements in installation. 90

The shape of the spacing portion 14 may be varied, in the instance illustrated in Figs. 4 and 5, such spacer portions 20 being illustrated of right angled outline. 95

In the modification of my invention shown in Fig. 5, each clip terminal portion 21 is preformed to be bent inwardly, see 22, i. e., 10

toward its body portion and flared outwardly at its terminal portion.

In the form of my invention illustrated in Fig. 6, the end portions 23 are not preformed, 5 and are adapted to be bent manually by the operative at the time of assembly and installation about an I-beam or other structural element.

Fig. 6 also illustrates the interconnecting 10 by welding at 18 of a plurality of re-enforcement sections by a plurality of interconnecting wires 19, 19, for the assembly of multiple re-enforcement sections.

In Fig. 7, I have illustrated a further modification, particularly the obverse direction 15 of extension of the inner terminal spacers 24, 24, in this instance serving as form spacers. A bottom mold board is indicated at 25.

A further variation of arrangement of the 20 individual portions of my re-enforcement sections have an inner spacer 17 engaging at its terminus the lower face of the flange 11 and the form spacer extension 24 extending in the opposite direction, as appears in Fig. 8.

25 All similar parts of the respective forms of my invention illustrated in the drawings are designated by like reference characters.

The material of the sections is usually of 30 wire, but other metal stock of suitable shapes may be employed.

Whereas, I have described my invention by reference to specific forms thereof, it will be understood that many changes and modifications may be made without departing from 35 the spirit of the invention.

I claim:—

1. A re-enforcement for concrete formed 40 of sections connected to one another, each section having an inner preformed spacer terminal and an intermediate spacer portion and a preformed outer terminal portion.

2. A re-enforcement for concrete formed 45 of a plurality of sets of re-enforcement sections, said sections being substantially duplicates of one another, each of said sections having an inner pre-formed spacer terminal and a wire interconnecting said sets to one another.

3. A re-enforcement for concrete formed 50 of a plurality of sets of substantially duplicate re-enforcement sections, each of said sections having a pre-formed outer terminal portion and a pre-formed intermediate spacer portion and a wire interconnecting said sets to one another.

4. A re-enforcement for concrete formed 55 of a plurality of sets of re-enforcement sections, each section having a pre-formed outer terminal portion and a pre-formed intermediate spacer portion, and a wire interconnecting said sets to one another.

5. A re-enforcement for concrete formed 60 of a plurality of sets of substantially duplicate re-enforcement sections, each section having a pre-formed outer terminal portion,

a pre-formed inner spacer terminal and a pre-formed intermediate spacer portion, and a wire interconnecting said sets to one another.

6. A re-enforcement for concrete formed 70 of a connected pair of substantially duplicate sections, each section having a pre-formed outer terminal portion and an intermediately disposed spacer portion, one of said pairs having a preformed inner spacer 75 terminal.

7. A re-enforcement for concrete formed 80 of a plurality of pairs of re-enforcing sections, the sections of each pair having a pre-formed intermediate spacer portion, one section of each pair having a pre-formed inner spacer terminal and a wire inter-connecting 85 said pairs with one another.

In testimony whereof I have signed this 35 day of March, 1929.

FREDERICK D. KREUDER.
